UNITED STATES PATENT OFFICE.

HAROLD S. SINES, OF CHICAGO, ILLINOIS, ASSIGNOR TO MINERALLAC ELECTRIC COMPANY, OF CHICAGO, ILLINOIS, A CORPORATION OF ILLINOIS.

ELECTRICAL CONNECTOR.

1,198,674.

Specification of Letters Patent. Patented Sept. 19, 1916.

Application filed February 23, 1915. Serial No. 9,865.

To all whom it may concern:

Be it known that I, HAROLD S. SINES, a citizen of the United States, residing at Chicago, in the county of Cook and State 5 of Illinois, have invented certain new and useful Improvements in Electrical Connectors, of which the following is a full, clear, concise, and exact description, reference being had to the accompanying drawings, forming a part of this specification.

My invention relates to electrical connectors and more particularly to devices adapted to serve as the terminals of electric conducting wires as connected with binding 15 posts or bolts of electrical generating or translating devices.

My invention contemplates the provision of a connector that may be manufactured at an extremely low cost, and one which may 20 be operatively connected with an associated conductor quickly and with a minimum of effort.

My invention will be more clearly understood by reference to the accompanying 25 drawings, in which:

Figure 1 illustrates in elevation the connector of my invention; Fig. 2 is a central cross-sectional view thereof; Fig. 3 is an elevation of the connector attached to an electrical conducting wire; Fig. 4 is a central cross-sectional view of the completed connection, as shown in Fig. 3; Fig. 5 is a top elevational view of a modified form of connector; Fig. 6 illustrates a complete electrical circuit employing the electrical connectors of my invention; Fig. 7 illustrates a modified form of the connector of my invention, and Fig. 8 shows a connector embodying my invention, the modified construction 30 illustrated in this figure being particularly desirable when a connector of comparatively large size and heavy material is required.

In Figs. 1 and 2, I have illustrated a connector formed of drawn brass or copper, and 45 comprising a hollow, substantially cylindrical shank 11, formed integrally with an annular base 12, the said base 12 being dished or upturned at its outer edge, as indicated at 13, and a flat annular top section 14, lying in a plane substantially normal to the axis of the shank 11. The length of the shank 11 is such that a stranded or solid wire or conductor may be inserted between the flanges 12 and 14, as indicated in Fig. 1, 50 and moreover the opening at 15 between the

upwardly turned peripheral edge of the flange and the periphery of the flange 14 is such as to permit the easy insertion of the wire or conductor. When the wire or conductor has been looped about the shank 11 60 and tightened to a greater or less degree, as indicated in Fig. 1, the upper flange 14 is pressed downwardly by means of a hammer, plier or other tool, so as to grip the wire or cable tightly between the flanges 12 65 and 14, as shown, the peripheral edge of the flange 14 being brought substantially into engagement with the peripheral edge of the flange 12 or brought within the upturned peripheral edge of the flange 12 so as to make 70 a smooth and finished terminal for the conductor 16 as shown in Fig. 3. The end 17 of the wire or conductor may if desired be twisted about the continuing portion of the wire, or that portion extending away from 75 the shank.

In Fig. 5 I have illustrated a modified form of my invention in which for convenience in forming, particularly in larger sizes, the connector is rolled instead of 80 drawn, and for this reason slotted at one side, as indicated at 18. This figure illustrates also a modified form of the lower flange in which the peripheral edge 13 is 85 not upturned throughout the entire circumference, this peripheral edge being flat and lying in the plane of the balance of the flange 12 at the points 19 and 20. When this embodiment of my invention is employed, the conductor or wire is led over 90 the flattened portion 19 or 20 and thence around the shank of the connector, thus obviating the necessity for passing the wire or conductor over the upturned edge of the lower flange 12, as would be the case in the 95 forms illustrated in Figs. 1, 2, 3 and 4. Two flattened portions, 19 and 20, will prove desirable in some cases, particularly where two wires or conductors are looped about the same shank or in case a wire is led wholly 100 or partly around the shank and then on to some more distant point.

In Fig. 6, I have illustrated an electromagnetic translating device 21 in the form of a relay or drop, and in which the terminal 105 wires of the electromagnet winding are connected with binding posts 22 and 23. In this figure I have illustrated diagrammatically an electric circuit comprising a battery or other source of electricity 24, a key 110

or switch 25 and wires 26 and 27 to the end of each of which is applied a connector, such as previously described. The connectors are slipped over the binding posts, as shown in Fig. 6, and there clamped in place.

In Fig. 7 I have indicated the manner in which my invention may be applied to connectors having a plurality of shanks about each of which one or more wires may be looped and clamped in position. In this form of my invention there is provided a common base plate 28, having upwardly turned peripheral edges at 29 and 30, the top flanges 31 and 32 are substantially like those shown in Figs. 1 to 5 inclusive, the conductors 33 and 34 are looped about the cylindrical shanks 35 and 36 and the flanges hammered or pressed down to engage the loops, as previously described. The peripheral edges of the common flange 28 may be flattened at one or more points, as indicated at 19 and 20 in Fig. 5, if desired.

The connector construction illustrated in Fig. 8 may be conveniently employed when a connector formed of relatively heavy material is desired. The connector illustrated in this figure comprises an annular base section 40, peripherally upturned as illustrated at 41. A hollow central shank illustrated at 42 is formed integrally with the base section 40, and formed integrally with the shank 42 is an upwardly flaring frusto-conical flange 43. This connector is preferably formed of relatively heavy material and for this reason, if when a wire is clamped between the upper and lower flanges, it should be necessary to distort the shank 42 to any considerable extent, it will be seen that a great amount of force would be required. As illustrated the shank 40 is comparatively short and when a conductor 44 is looped around the shank it is merely necessary to force the periphery of the up-

wardly flaring frusto-conical flange to the position indicated by dotted lines to securely retain the conductor in proper position.

Having thus described my invention, what I claim as new and desire to secure by Letters Patent of the United States is:

1. A connector of the class described, comprising a hollow shank adapted to having a conductor looped therearound and adapted to be passed over a binding post, an annular flange formed integrally with the shank at the lower end of the latter and disposed in a plane substantially normal to the axis of the shank, said annular flange being provided with an upturned lip at its periphery, and an annular flange formed integrally with the upper end of the shank, said last mentioned flange being of less width than the lower flange and arranged to be forced down within the upturned peripheral lip of the lower flange to clamp the conductor in position around the shank.

2. A one piece connector of the class described, comprising a short hollow shank adapted to have a conductor looped therearound, an annular flange formed integrally with the shank at its lower end and disposed in a plane substantially normal to the axis of the shank, and an upwardly flaring substantially frusto-conical flange formed integrally with the upper end of said shank and adapted to have its periphery forced down toward the lower flange to securely clamp the conductor in position around the shank.

In witness whereof, I hereunto subscribe my name this 17th day of February, A. D. 1915.

HAROLD S. SINES.
